United States Patent Office

Des. 229,907

Patented Jan. 15, 1974

229,907

LOUNGE CHAIR

Don Ray Gill, 792 Dodge Trail,
Westville, Ind. 46391

Filed June 1, 1971, Ser. No. 149,114

Term of patent 14 years

Int. Cl. D6—01

U.S. Cl. D6—39

The figure is a perspective view of a lounge chair illustrating my new design. The back of the lounge chair is conventionally plain while the side not shown is substantially identical to the side shown.

I claim:

The ornamental design for a lounge chair, as shown and described.
